FROZEN CONFECTION

Ludwig H. Baier, Hollis, N. Y., assignor, by mesne assignments, to Fruit Products Corporation, New York, N. Y., a corporation of New York

Application August 18, 1949, Serial No. 4,591

Term of patent 14 years

(Cl. D82—2)

To all whom it may concern:

Be it known that I, Ludwig H. Baier, a citizen of the United States and residing at Hollis, in the county of Queens and State of New York, have invented a new, original, and ornamental Design for Frozen Confection, of which the following is a specification, reference being had to the accompanying drawings, forming part thereof, and in which:

Fig. 1 is a perspective view of a frozen confection showing my new design,

Fig. 2 is a side elevation thereof, and

Fig. 3 is a top plan view thereof.

I claim:

The ornamental design for a frozen confection, substantially as shown.

LUDWIG H. BAIER.
